UNITED STATES PATENT OFFICE.

DAVID G. DEE, OF ROCHESTER, NEW YORK, ASSIGNOR TO DENIO GENERAL ELECTRIC COMPANY, OF ROCHESTER, NEW YORK, A CORPORATION OF NEW YORK.

FIRE-ALARM APPARATUS.

1,194,723.

Specification of Letters Patent. Patented Aug. 15, 1916.

Application filed July 25, 1912. Serial No. 711,471.

To all whom it may concern:

Be it known that I, DAVID G. DEE, of Rochester, in the county of Monroe and State of New York, have invented certain new and useful Improvements in Fire-Alarm Apparatus; and I do hereby declare the following to be a full, clear, and exact description of the same, reference being had to the accompanying drawings, forming a part of this specification, and to the reference-numerals marked thereon.

My present invention relates to fire alarm apparatus, particularly to systems to be used in conjunction with the subscribers' lines of telephone exchange systems and it has for its object to provide means for giving a distinctive signal to the exchange operator whereby the fire alarm call may be readily distinguished from line troubles or an improper use of the telephone apparatus by the subscriber.

To these and other ends the invention consists in certain improvements and combinations of parts, all as will be hereinafter more fully described, the novel features being pointed out in the claims at the end of the specification.

In the drawings: Figure 1 is a diagrammatic view illustrating a call mechanism showing one embodiment of my present invention, and Fig. 2 is a detail view showing a modification thereof.

The apparatus embodying my present invention is adapted to use in municipalities provided with telephone exchange systems, the fire alarm signaling or calling instruments used in conjunction therewith being adapted when set into operation, to transmit to the exchange operator, in addition to the impulses of current indicating the code signal of the instrument, other impulses which vibrate the diaphragm of the operator's telephone receiver, to audibly indicate that an alarm has been turned in. The distinguishing signal is such that it may be immediately recognized by the exchange operator and not misunderstood, as a possible line disturbance, such as an intermittent ground applied to the circuit, or other line trouble. The provision of means whereby the central office operator may be quickly informed of the character of the signal possesses the advantage that it is unnecessary to wait until the signaling apparatus has been in operation for a length of time sufficient to permit a full

signal or "round" of the box to be turned in, which would otherwise be necessary to distinguish such signal from some other effect which might be produced on the telephone line from outside causes. The idea of quickly informing the telephone operator at the central exchange of the character of the call which is being received is important in that the calling circuit may be more quickly connected to the fire department headquarters and a direct connection established between the subscriber's alarm or calling apparatus and the alarm sounding and recording devices of the fire department.

The present invention is applicable to any form or type of signal box which may be employed for transmitting a series of current impulses, or such impulses arranged in groups, the transmission of which will indicate an alarm for some particular purpose despatched over the telephone subscriber's instrument circuit.

In illustrating my present invention, I have shown a telephone subscriber's instrument circuit, comprising the line wires A—B leading from the tip and sleeve contacts of the switch-board jack J; said subscriber's circuit comprising the transmitter T and the receiver R, suspended on the usual receiver hook r. The alarm mechanism indicated by M may be located at any convenient point and will preferably comprise a clock train signal mechanism having the frame m and the notched wheel n carrying the contact pin o which when the parts are in their normal position, as shown in Fig. 1, is in engagement with the spring p. A second insulated spring q is arranged as shown and adapted to close the circuit between the two sides of the telephone line, when the projections on the signal wheel n engage therewith. This signal mechanism is interposed in the line circuit, by carrying one side thereof, as the line wire A, to a point of contact with the frame m and extending it as indicated by A' from the contact spring p.

The central office apparatus, or switch-board mechanism, may be of the usual or any preferred construction and in the illustrations I have shown diagrammatically the answering and calling cord circuits indicated by 1 and 2 respectively, receiving current from the battery 3, in circuit with which is the operator's set comprising the receiver 4 and the transmitter 5. Associated with the 110

jack J is the pilot lamp *j*, arranged in a circuit which is closed by the springs of the jack J when these are in their normal position, so that the pilot lamp will be lighted to 5 signal the central operator when the subscriber closes his circuit by removing his receiver from the hook *r*. In systems of this character a separate call circuit on the switchboard is provided for the line leading 10 to the fire department headquarters, comprising a plug *S* from the tip and sleeve contacts of which extend the line wires *s*—*s'*. This private circuit is fed with current from a battery or other source of current *s*² for 15 actuating an electro-magnet *s*³ controlling an armature *s*⁴ which is adapted to be moved into engagement with the contact *s*⁵; said armature and contact being in a local circuit at the fire alarm headquarters comprising 20 the wires *s*⁶ and *s*⁷ connecting the battery *s*⁸ and the electro-magnets *s*⁹, by means of which the punch or marker *s*¹⁰ is operated to record the fire alarm signal on a tape *s*¹¹.

The object of my invention is to provide 25 in conjunction with the circuit and alarm indicating mechanism described, means arranged in the alarm circuit whereby a distinctive signal is simultaneously transmitted over the line circuit with the transmission 30 of the impulses of the alarm code. In the ordinary operation of the alarm mechanism the pilot lamp *j* will flicker or flash, in response to the impulses of current transmitted over the line circuit by the signaling 35 mechanism. These flashes occurring at regular predetermined intervals and indicating the number of the fire alarm box in operation, cannot be distinguished by the central operator, as the pilot light may be 40 similarly operated from other disturbances on the telephone line, as for instance, by the opening and closing of the receiver hook contact of a telephone set; an intermittent ground applied to the line; or an occasional 45 short circuit thereon. For these reasons it is impossible for the central office operator to determine immediately between such causes of trouble and the regular operation of the fire alarm box. This necessarily 50 causes delay in transmitting the signal to the fire headquarters, because if the operator is to make sure that the signal received is a proper fire alarm signal, it is necessary to wait until, at least, one complete "round" 55 of the signal box has been transmitted. This also retards the traffic on the switchboard, as the operator during this time, is prevented from responding to other calls.

The distinctive signal which I propose to 60 use, is an audible one received by the central office operator in the receiver 4, produced by superimposing an induced current of frequent alternations on the circuit, when it is closed through the signal box. One 65 means of carrying out the invention con-

sists in extending from the side B of the circuit a branch B' which leads to the normally open contact spring *g*. The subscriber's instrument set is cut out when the numeral wheel *n* is rotating at the contacts 70 *p* and *o*. Provided in the branch B' of the circuit is an electro-magnet, having the windings *b*' and the pole pieces *b*² in proximity to the free ends of which is arranged an armature C. Relative movement 75 between the armature and the pole pieces is effected by mounting one of these parts, as for instance, the armature, in such a manner that it may be vibrated or agitated mechanically during the operation of the 80 alarm mechanism to vary the air gap between said armature and the pole pieces of the magnet, which causes a change in the magnetic flux flowing therethrough and generates or induces in the winding of the 85 magnet an alternating current thus superimposing on the line a current which produces a distinctive signal. It is preferable 90 that the vibration of the armature C should be rapid, and to this end it may be conveniently supported, as shown in Fig. 1, and agitated by a hammer or clapper *m* operated by the detent *m*² which controls the speed of operation of the clock train.

In Fig. 2 I have shown a modified arrangement of the parts in which the wire B¹⁰, corresponding to the wire B', is provided with the winding *b*¹¹ of an electro-magnet, having the core pieces *b*¹², which are rigidly supported on the casing M¹⁰ of the signal apparatus. In this form of the device the armature C¹⁰ is shown supported upon the extremity of a spiral spring C¹¹, the inner end of which is attached to a rigid post C¹², extending outwardly from the 100 rear wall of the case M¹⁰, in such position that the spring may be struck by the vibrating hammer *m*¹⁰. This form of apparatus may be employed where it is desired 105 to sound a warning signal in the alarm box 110 for the benefit of persons who may be in that vicinity as well as to provide the distinctive signal for the central office operator.

In operation, the alarm mechanism, having been actuated or set into action in the usual well known manner, becomes bridged across the subscriber's line circuit and each time said circuit is closed through the projections on the wheel *n* and wiper *g* the pilot light J attracts the central office operator's attention. The latter then places the answering plug 1 in the jack J and during the periods the circuit is closed the operator 115 distinguishes the peculiarity of the audible signal, whereupon the answering plug 1 is removed and the special plug *S* of the fire alarm circuit is inserted in the jack J. The intermittent impulses of current then flowing over the circuit *s*—*s'* energizes the mag- 120 125 130

net s^3 , causing a corresponding operation of the armature s^4 and the recording device operated by the local circuit comprising the wires s^6 , s^7 .

5. I claim as my invention:

1. The combination with a telephone system provided with an operator's receiver and subscriber's line circuits leading from the exchange, and subscriber's line signal, and a central battery current, of a fire alarm apparatus comprising a normally open alarm circuit in conjunction with the subscriber's line circuit, an alarm mechanism adapted to close and open said alarm circuit, means operated thereby to operate the line signal, and means operated by the alarm mechanism for superimposing an alternating current on said circuit when closed in addition to the battery current to produce an audible signal 20 in the central operator's receiver.
2. The combination with a telephone system comprising an exchange and subscribers' line circuits leading therefrom and supplied with battery when closed, each subscriber's line circuit being provided with a line signal, of a fire alarm apparatus comprising a normally open alarm circuit in conjunction with the subscriber's line circuit, an electro-magnet in said alarm circuit, an alarm mechanism adapted to cause current in said circuit to flow by impulses for operating the line signal aforesaid, and means for varying the magnet flux in the core of said magnet, during the transmission of such impulses, 35 said flux variations producing an induced current in the winding of the magnet which is impressed upon the line circuit when the alarm circuit is closed.
3. The combination with a central energy 40 telephone system comprising subscribers' line circuits which are normally open and are supplied with battery current from a central source when closed, each subscriber's line circuit being provided with a central office line signal, of a fire alarm mechanism adapted to cause said current to flow by impulses over a subscriber's line circuit and thereby operate the line signal thereof, and means actuated by said mechanism for imposing an alternating current on said circuit during the transmission of the impulses.

4. A fire alarm system for telephone lines comprising a normally open circuit leading from the said line and adapted when closed 45 to close the line circuit and to be energized by the current supplied to said line from the usual source, of an electro-magnet arranged with its coil in said circuit and means cooperating with the pole pieces of said magnet for varying the magnetic flux flowing through the core of the magnet and means for closing and opening the alarm circuit.

5. A fire alarm system for telephone lines comprising a normally open circuit leading 50 from the said line and adapted when closed

to close the line circuit and to be energized by the current supplied to said line from the usual source, of an electro-magnet having pole pieces located adjacent and arranged with its coils in said circuit, of an armature 70 co-operating with said pole pieces, means for effecting a relative movement between the pole pieces and armature to vary the air gap between them and means for closing and opening said alarm circuit.

6. The combination with a subscriber's telephone circuit and a central office equipment comprising an operator's receiver and an alarm mechanism associated with the circuit for transmitting current impulses thereon by opening and closing said circuit, of a magnet winding interposed in the circuit, and an armature therefore, arranged to be vibrated by the operation of the alarm mechanism to induce an alternating current in the 85 magnet which is superposed on the circuit to produce a distinctive audible signal in the operator's receiver.

7. The combination with a telephone system comprising an exchange having an operator's receiver and subscriber's line circuits and provided with current from a central source, of a fire alarm apparatus comprising a normally open alarm circuit, an alarm mechanism adapted to open and close 90 said alarm circuit and subscriber's line circuit for transmitting an alarm signal over said alarm and subscriber's line circuits, means controlled thereby to operate a line signal, and means operating upon the subscriber's line and alarm circuits for generating and superimposing an alternating current upon said circuits when said alarm circuit is closed, in addition to the alarm signal 95 impulses, to produce an audible and distinctive signal in the operator's receiver.

8. The combination with a telephone system comprising an operator's receiver and subscriber's line circuits and provided with battery current from a central source, of an 110 alarm apparatus associated with the subscriber's line circuit comprising a normally open alarm circuit and an alarm mechanism adapted to open and close both the alarm circuit and the subscriber's line circuit, thereby transmitting alarm signal impulses over said circuits from the central source of battery current, means controlled thereby to operate the line signal, and means operable by the alarm mechanism for superimposing an alternating current on said alarm circuit and said subscriber's line circuit, when closed, in addition to the signal impulses aforesaid to produce an audible distinctive signal in the operator's receiver.

9. The combination with the telephone system comprising an exchange provided with an operator's receiver and subscriber's line circuits and a line signal, of an alarm apparatus comprising a normally open cir- 120

cuit associated with the subscriber's line circuit, an alarm mechanism adapted to open and close said alarm circuit and said subscriber's line circuit, thereby sending alarm signal impulses over said circuit which operate the line signal, and means associated with the alarm circuit for superimposing an alternating current on said alarm circuit and said subscriber's line circuit upon the closing

of said circuits in addition to the signal impulses transmitted by the alarm mechanism, thereby producing a distinctive and audible signal. 10
